UNITED STATES PATENT OFFICE.

SOL EINSTEIN, OF CINCINNATI, OHIO, ASSIGNOR TO CINCINNATI MILLING MACHINE COMPANY, OF CINCINNATI, OHIO, A CORPORATION OF OHIO.

DIAL-OPERATED CHANGE GEAR.

Application filed November 20, 1923. Serial No. 675,879.

To all whom it may concern:

Be it known that I, SOL EINSTEIN, a citizen of the United States, and residing at Cincinnati, in the county of Hamilton and

5 State of Ohio, have invented a new and Improved Dial-Operated Change Gear, of which the following specification is a full disclosure.

This invention deals with machine tools 10 and relates more particularly to a change-gear mechanism for varying the speed of travel of one element thereof with respect to another element. The present invention is adaptable among other machines, to milling 15 machines and is disclosed and described in connection with a table feeding mechanism for such a machine only as one typical embodiment thereof.

In milling machines it is essential that 20 the table and the work carried thereon be translated with respect to the tool at a speed determined by the nature of the work. As the rate of feed is necessarily changed frequently, efficiency in action of the speed 25 change mechanism and convenience of location and manipulation of the controlling means therefor are highly important features of these machines.

This invention has for an object to provide 30 an improved form of speed change mechanism which will produce the necessary variety of feeds of the table from a single speed drive shaft.

A further object of the invention is to 35 provide a simplified means for selectively shifting the various gears of the speed change mechanism and so to construct and locate the shifting means therefor that the attendant may effect any desired table feed 40 without leaving his station before the work.

A still further object is to provide a gear shift mechanism by which all of the gear changes are effected by a single manually actuated element having only a circular 45 movement.

Other objects and advantages will be in part indicated in the following description and in part rendered apparent therefrom in connection with the annexed drawings.

50 To enable others skilled in the art so fully to apprehend the underlying features hereof that they may embody the same in the various ways contemplated by this invention, drawings depicting a preferred 55 typical construction have been annexed as a

part of this disclosure and, in such drawings, like characters of reference denote corresponding parts throughout all the views, of which:—

Fig. 1 is a perspective view of a milling 60 machine embodying the present invention. Fig. 2 is a development of the change gear mechanism and the manually controlled means for shifting the gear members. Fig. 3 is a vertical section taken at right angles 65 to Fig. 2 through a portion of the knee showing certain gear shifting yokes later to be referred to. Fig. 4 is a section somewhat similar to Fig. 3 but showing a detent means for preventing accidental shifting of 70 the gears. Fig. 5 is a detail plan partly in section of the mechanism shown in Fig. 4. Fig. 6 is a diagrammatic view showing the means for intermittently actuating one gear shifting element from another gear shifting 75 element. Fig. 7 is a front elevation of the manually actuated gear shift controlling lever together with the indexed dial associated therewith for indicating the rate of table feed in any position of the lever. 80 Fig. 8 is a development somewhat similar to Fig. 2 but showing a modified construction. Fig. 9 is a view similar to Fig. 3 but showing the modified construction of Fig. 8. Fig. 10 is a diagrammatic view of the gear shift- 85 ing cam groove shown in Fig. 8.

Referring more particularly to the drawings the invention is disclosed as embodied in a typical milling machine comprising a base Z supporting an upright column X 90 upon which is vertically adjustable the usual knee K. Upon the knee is slidably mounted the saddle S within which the table T is endwise movable. Journalized in suitable bearings 9 in the knee is a suitably pro- 95 pelled driving shaft 10 having a constant speed of rotation, and a driven shaft 11 adapted to be driven at any one of a number of predetermined speeds as will later be described. The shaft 11 has secured to it a 100 pinion 12 meshing with a gear 13 which, through a suitable friction clutch 14 rotates a gear 15 operatively connected to turn the feed screw 16 to effect translation of the table. As the means for rotating the feed 105 screw 16 from the gear 15 is of conventional form and forms no part of the present invention, detail illustration and description thereof is deemed unnecessary.

Splined upon the shaft 10 are two gear 110

- units A and B. The unit A consists of gears 1 and 2 adapted, by the manipulation of a suitable hand-lever selectively to be brought into mesh with gears 1^a and 2^a of a gear-unit F loosely journaled on bushings 18 supported by an intermediate shaft 19 also carried by the knee. The second gear-unit B consists of gears 3 and 4 likewise adapted to be selectively brought into mesh with gears 3^a and 4^a also forming a part of the gear-unit F. The intermediate shaft 19 has fixedly secured upon it relatively large and small gears 7 and 8 later to be referred to.
- 15 Non-translatably journaled upon bushings 20 surrounding the driven shaft 11 is a sleeve 21 at one end of which is integrally formed a gear 7^a permanently in mesh with gear 7, and a clutch element comprising a series of clutch teeth 22. A third shiftable gear-unit C is splined to the sleeve 21 and carries gears 3^b and 5^a adapted to selectively be brought into mesh respectively with the gears 3^a and 5 on the gear-unit F.
- 20 Splined to the shaft 11 is a fourth shiftable gear-unit D formed at its opposite ends with a gear 8^a, adapted to mesh with the gear 8, and a series of clutch teeth 23 adapted to engage the clutch teeth 22 of the sleeve 21.
- 25 The unit D, in addition to effecting one of the speed changes, also acts as a connecting element between all of the change-gears and the shaft 11, it being fixed to that shaft.
- 30 From the foregoing it will be observed that from the single speed drive-shaft 10 four speeds are given the unit F. These four speeds are multiplied into eight speeds by the gear-unit C. Any one of these eight speeds may be transmitted to the driven shaft 11 by shifting the unit D to the right as viewed in Fig. 2 to effect engagement of the clutch teeth 22 and 23, or the eight speeds may be further multiplied into sixteen speeds by shifting the unit D to the left to mesh the gears 8 and 8^a, the unit D in each instance being the element that rotates the shaft 11.
- 35 An important feature of this invention resides in the mechanism for shifting the various gear-units to selectively give to the table T any one of the above described sixteen speeds. Various forms of devices have heretofore been employed for this purpose such as a plurality of manually actuatable levers or a single element movable in different planes to various positions of adjustment. This invention provides an improved form of gear shifting mechanism whereby any one of the available rates of
- 40 table feed may be conveniently effected by a single controlling element having only a circular movement. This mechanism is so constructed and arranged as to permit any desired higher feed rate to be attained
- 45 through a series of progressive gear shifts each of which is slightly faster than the former, whereby the clashing of fast and slow running gears of earlier constructions is eliminated. Obviously the converse, i. e., the like shifting to a slower feed, is also, true. The gear shifting mechanism herein disclosed is also novel in that it precludes improper setting of the gears, and also in that the feed rate is indicated by the position of the controlling element with respect to the adjacent fixed index which may readily be observed by the attendant when stationed before his work.
- 50 Referring particularly to Figs. 2 to 7 it will be observed that within the knee there are journaled, parallel with the shafts 10, 11 and 19, two cylinders G and H geared together by means of interrupted gears g and h where by a continuous rotation of the cylinder G effects an intermittent rotation of the cylinder H for a purpose later to be described. In the outer surface of the cylinder G are formed two cam-grooves a and b respectively; similar cam grooves c and d being formed in the cylinder H.
- 55 Journaled within the knee are two primary gear-shifting yokes. These yokes are similar in construction and therefore only one has been shown and described. The yoke 24 is journaled upon a pin 25 fixed in the knee and carries a stud or roller 26 which tracks the cam groove a. This yoke is also formed with a forked end 27 which extends into an annular groove 28 formed in the gear-unit A and under the action of the cam groove shifts the gear-unit lengthwise of the shaft 10. A similar yoke has a stud or roller tracking the cam-groove b and has its forked end cooperating with the annular groove 29 in the gear-unit B for shifting said unit lengthwise of the shaft 10. Means for shifting the gear-units C and D lengthwise of the shaft 11 consist of two secondary yokes journaled within the knee K. These yokes also are similar and therefore only one is shown and described. The yoke 30 is journaled upon a rod 31 carried by the knee and is provided with a stud or roller 32 which tracks the cam-groove c. The forked end 33 of the yoke 30 fits within the annular groove 34 in the gear-unit C. A second yoke similar to the yoke 30 has a stud or roller tracking the cam-groove and has a forked end engaging the gear-unit D.
- 60 To effect rotation of the cylinders G and H there is journaled in the forward end of the knee a stub shaft 35 to which is fixedly secured an actuating element herein shown as a hand-crank 36. Also secured upon the shaft 35 is a gear 37 having internal teeth 38 which mesh with and rotate a pinion 39 upon one end of the cylinder G. The opposite end of the cylinder G is formed with detent notches 40 which cooperate with a spring depressed detent member 41 pivoted

at 42 to the knee and carrying a roller 43 which holds the cylinder against accidental rotation.

An index dial 44 is secured upon the forward end of the knee co-axial with the shaft 35 and intermediate the crank 36 and the gear 37. This dial is provided with a series of markings representing the various table-feeds obtainable. As shown by Fig. 7 the feed of the table may be progressively increased by rotating the crank counter-clockwise, it being understood that the cam-grooves in the cylinders are so arranged as to shift the gear units A, B, C and D in the proper sequence to produce the feed indicated by the position of the member 36.

To effect a variable motion between the cylinders G and H to cause the cam grooves to shift the gear-units in the proper sequence, the continuously rotatable cylinder G preferably carries a gear member g provided with a single series of teeth g' (see Fig. 6). This series is adapted to mesh with four similar series h' formed in a gear member h secured to the cylinder H; the convex blank g^x of the member g fitting within the concave blanks h^x of the member h thereby preventing rotation of the cylinder H when the teeth g' and h' are out of mesh.

The operation of this speed-change mechanism is as follows:—Suppose it is desired to give the table its slowest possible feed from a predetermined speed of the shaft 10, the crank 36 will be turned until it covers the lowest value indicated on the dial 44 that is, as represented "3/4", it being understood that in Fig. 7 the member 36 covers the value representing the highest rate of feed. This partial rotation of the crank 36 through the connections previously explained partially rotates the cylinders G and H and this rotation causes the cam-grooves a, c and d, through the yokes 24 and 30, to shift the gear-units A, C and D to mesh the gears 2 and 2^a, 5 and 5^a, and 8 and 8^a, the roller extending into the cam b, then tracking a neutral portion of said cam so that the gear-unit B is not shifted from its neutral position. The gear-unit C being splined to the sleeve 21 which carries the gear 7^a power is transmitted through the gear 7^a to its mate 7 which in turn rotates the shaft 19 carrying the gear 8. Thus it will be seen that an operative connection is established between the driving shaft 10 and the driven shaft 11 which latter through suitable conventional mechanism translates the table T, the gear-unit D being the element that drives the shaft 11.

The predetermined highest rate of feed may likewise be obtained from any lower feed rate by turning the member 36 to the position shown in Fig. 7, thereby meshing

the gears 3 and 3^a, 3^a and 3^b and the clutch teeth 22 and 23, the gear-unit D being the element that drives the shaft 11. Obviously any desired feed between the extremes may be obtained by the proper setting of the crank 36.

In the modification shown in Figs. 8, 9 and 10 the hand-lever 36' is secured directly upon the reduced end of a cylinder I within which are cut cam-grooves a', b', c', and d' adapted to actuate the yokes 24 and 30 to shift the gear-units A, B, C and D, similar to the cam grooves a, b, c, d, previously described. The cylinder I being affixed to the hand-lever 36' receives a positive motion therefrom. The cam grooves a', b', c' and d' are each formed with active portions v and neutral portions n which are so related to each other that the gear-units A, B, C and D are shifted in the proper sequence.

The cylinder I is preferably provided with a toothed disk 40 which cooperates with a spring-pressed detent 41 to prevent accidental rotation of the cylinder I.

It is to be understood that a conventional reversing mechanism may be associated with the present table feeding mechanism but as such reversing mechanism forms no part of the present invention it is not deemed necessary to illustrate or describe the same.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims:

Having thus revealed this invention, I claim as new and desire to secure the following combinations and elements, or equivalents thereof, by Letters Patent of the United States:

1. In a speed-change mechanism for a machine tool constructed with a knee, a saddle, and a table translatable mounted on said saddle, in combination a driving shaft and a driven shaft journaled in said knee; an operative connection between said driven shaft and said table for translating the latter from the former; an intermediate shaft; a plurality of gears non-translatable supported upon said intermediate shaft; a plurality of shiftable gear-units carried by said driving and driven shafts and adapted selectively to be engaged with the gears on said intermediate shaft; a rotatable member journaled in said knee; a plurality of cams

- formed on said rotatable member; a plurality of yokes journaled in said knee and each operatively connecting one of said cams with one of said shiftable gear-units; and a 5 single means carried by said knee for rotating said rotatable member to selectively engage said gear-units to cause said driven shaft to translate said table at any one of a plurality of predetermined speeds.
- 10 2. A speed change mechanism combining a driving shaft; a driven shaft; an intermediate shaft; translatable gear-units carried by said driving and driven shafts; non-translatable gears cooperating with said 15 gear-units carried by said intermediate shaft; means for shifting said translatable gear-units to effect an operative connection between said driving and driven shafts; said means comprising a first and a second rotatable cylinder formed with peripheral cam grooves; non-translatable gear shifting yokes connected to said shiftable gear units and actuated by said cam-grooves, means for giving said first rotatable cylinder an uninterrupted rotation and a connection between said rotatable cylinders for giving to the 20 second an intermittent rotation from the uninterrupted rotation of said first cylinder.
- 30 3. In a speed-change mechanism for a machine tool constructed with a knee, a saddle, and a table translatable mounted on said saddle, in combination, a driving shaft journaled in said knee; a shiftable gear-unit splined to said driving shaft; an intermediate shaft; non-translatable gears journaled co-axial with said intermediate shaft; two 35 gears fixed to said intermediate shaft; a driven shaft journaled in the knee; a shiftable gear-unit co-axial with said driven shaft; a non-translatable gear co-axial with said driven shaft permanently in mesh with one of said two fixed gears; a rotatable cylinder journaled in said knee and formed with a plurality of peripheral cam grooves; 40 a plurality of gear-shifting yokes rotatably but non-translatable journaled in said knee, said yokes each being formed with a portion engaging one of said shiftable gear-units and a portion cooperating with one of said 45 cam-grooves; a rotatable crank carried by said knee for rotating said cylinder to cause said yokes to shift said gear-units and selectively produce any one of a plurality of 50 speeds in said driven shaft from a single speed in the driving shaft; an index affixed to said knee adjacent said crank for indicating, by the position of the crank, the feed selected; and means for translating said table from said driven shaft.
- 55 60 4. A change-gear mechanism combining a drive shaft; a driven shaft; shiftable gear-units supported by said shafts; an intermediate shaft; gears non-translatable supported by said intermediate shaft; means 65 for shifting said shiftable gear-units to cause the gears thereof to engage certain of said non-shiftable gears to produce various speeds in said driven shaft; said gear-shifting means including a plurality of cylinders providing a plurality of cam-grooves, one of 70 said cylinders also being formed with a plurality of detent notches; yokes connected with said shiftable gear-units and actuated by said cam-grooves; a pinion fixed to one of said cylinders; a gear meshing with said 75 pinion; a member having only a circular motion operatively connected to said last-mentioned gear for rotating the same; an interrupted gear connection between said cylinders for intermittently rotating one from the other to shift the gear-units in a predetermined sequence; and a single spring detent cooperating with said detent notches to hold said cylinders and thereby said yokes and shiftable gear-units in predetermined positions.
- 80 85 5. A speed-change mechanism combining a driving shaft; a driven shaft; an intermediate shaft; translatable gear-units providing a plurality of gears of varying sizes 90 carried by said driving and driven shafts; a non-translatable gear-unit providing a plurality of gears of varying size journaled coaxially with said intermediate shaft and cooperating with said translatable gear-units; 95 means for selectively meshing the gears of said gear-units to drive said driven shaft at any one of a number of predetermined speeds, said means comprising two parallel cam-cylinders each provided with two cam 100 grooves, and four yokes each engaging one of said cam grooves and one of said gear-units; a pinion carried by one of said cylinders; a relatively large gear engaging said pinion, said gear and pinion being ratioed substantially four to one; an interrupted gear carried by one of said cylinders and formed with a single series of teeth; an interrupted gear carried by the other of said 105 cylinders and provided with four series of teeth adapted successively to mesh with the single series; manual means for giving to said relatively large gear one complete rotation thereby giving to one of said cylinders four rotations and a single rotation to the other cylinder, whereby said gear-units are shifted in a predetermined sequence.
- 110 115 6. A change-gear mechanism combining a driving shaft; first and second gear-units each provided with two gears of unequal size splined thereto; a driven shaft; a sleeve non-translatable journaled co-axially with said driven shaft; a gear-member and a series of clutch teeth formed integral with 120 said sleeve; a third gear-unit splined to said sleeve, a fourth gear-unit splined to driven shaft and provided with a series of clutch teeth adapted in a certain position of adjustment to engage the clutch teeth on said sleeve; an intermediate shaft; a gear- 125
- 130

- unit non-translatable journaled co-axially with said intermediate shaft and formed with a plurality of gears adapted to mesh with said first, second and third gear-units; 5 a gear fixed to said intermediate shaft and maintained constantly in mesh with the gear on said sleeve; a second gear fixed to said intermediate shaft and adapted to mesh with the gear of said fourth gear-unit in 10 one of its positions of adjustment; and means for shifting said translatable gear-units to selectively engage certain of said gears to give to said driven shaft any one of sixteen predetermined speeds from a single predetermined speed of said drive shaft. 15 7. A change-gear mechanism according to claim 6, characterized by this that the means for shifting the gears comprises a rotatable member provided with a plurality 20 of cam-grooves; gear shifting members engaging the translatable gear-units and said cam grooves and actuated by the latter; and means for rotating said rotatable member. 8. A change-gear mechanism according to claim 7 characterized by this that the means for rotating the cam member comprises a hand-lever operatively connected to said cam member; that the cam grooves are so constructed and arranged that a continued turning movement of the hand-lever in one direction shifts the gears to produce a progressive increase in speed in the driven shaft from its lowest to its highest speed. 9. A speed change mechanism combining 35 a driving shaft; two shiftable gear-units splined thereto; an intermediate shaft; an intermediate gear-unit journaled co-axially with said intermediate shaft; means for shifting said shiftable gear units to selectively engage the gears thereof with the gears of said intermediate gear-unit; two gears fixed to said intermediate shaft; a driven shaft; a sleeve journaled co-axially with said driven shaft; a gear and a clutch 40 element carried by said sleeve, said gear permanently meshing with one of the gears fixed to said intermediate gear-unit; a gear-unit splined to said sleeve and provided with gears adapted to be brought into mesh with gears of said intermediate gear-unit; 45 a gear-unit splined to said driven shaft and provided with a gear and a clutch element; and means for shifting said last-mentioned gear-unit in one direction to engage the clutch-teeth thereof with the clutch teeth of 50 said sleeve and to shift it in the opposite direction to engage the gear thereof with one of the gears fixed to said intermediate shaft. 10. A change-gear mechanism combining 60 a drive shaft; a driven shaft; shiftable gear-units supported by said shafts; an intermediate shaft; gears non-translatable supported by said intermediate shaft; means for shifting said shiftable gear-units to 65 cause the gears thereof to engage certain of said non-shiftable gears to produce various speeds in said driven shaft; said gear-shifting means including a plurality of cylinders providing a plurality of cam-grooves; yokes 70 connected with said shiftable gear-units and actuated by said cam-grooves; a pinion fixed to one of said cylinders; a gear meshing with said pinion; a member having only a circular motion operatively connected to 75 said last-mentioned gear for rotating the same; and an interrupted gear connection between said cylinders for intermittently rotating one from the other to shift the gear-units in a predetermined sequence. 80

In witness whereof, I hereunto subscribe my name, as attested by the two subscribing witnesses.

SOL EINSTEIN.
